UNITED STATES PATENT OFFICE

ERNEST W. STACEY, OF BEVERLY, MASSACHUSETTS, ASSIGNOR TO UNITED SHOE MACHINERY CORPORATION, OF PATERSON, NEW JERSEY, A CORPORATION OF NEW JERSEY

REELING SYSTEM

Application filed January 2, 1929. Serial No. 329,702.

My invention relates to systems by which extended lengths or webs of sheet-material are coiled upon reels to arrange the material for convenient utilization. As herein disclosed, the invention is applied to thus disposing of sheet-rubber as it is delivered from calendering apparatus.

In coiling rubber as it emerges from calender-rolls, the practice heretofore has been to lead the end to a reel, together with one or more strips or webs of a liner or separator, and wind these together upon the reel. When the reel was filled and thus ready to be used or stored, it was removed from its support and another reel substituted for the repetition of the coiling operation. Since it is desirable that the action of the calender-rolls shall continue uninterruptedly and as the web of stock advances from them at a comparatively rapid rate, and further since the reels are heavy and difficult to handle, a considerable length of stock, fifty feet or more, will have come from the rolls before the next reel is ready to receive it. This loose end must be gathered up, severed from the advancing web and returned to be recalendered. Such a procedure results in a substantial loss of time. This invention has as an object the provision of a novel system for reeling material by which losses of the character just indicated will be eliminated. In the accomplishment of this object, I employ a movable support, preferably rotatable, upon which a plurality of reels are rotatable or otherwise movable. By this means, a reel which has been filled may, without delay, be carried out of its receiving relation by the support, another supported reel being simultaneously caused to assume its receiving position. While this second reel is receiving the stock, the first may be removed and another empty reel put in place for later use. Thus, the only delay is the very brief one required to shift the support. To prevent adhesion of the convolutions of stock to one another, it is customary to wind with it a separator and I therefore associate a separator-reel upon the support with a receiving reel, so that the former reel is not only held in the proper relation to the latter, but is also shifted with

it in the rotation of the support. When the full reel of material is taken from the support and an empty one substituted, the now empty separator-reel may be replaced by a full reel. I may prefer to employ two separator-webs, as a slatted formation which holds the stock without pressure upon it produced by the winding force, and a continuous web of relatively thin material. The latter may be interposed between the first-mentioned separator and the stock, and prevents flaccid material, as rubber, from sagging between the slats into contact with adjacent turns, and also guards such material from being indented by the edges of the slats. With this arrangement, one separator, as the slatted form, is first connected at its extremity to the receiving reel, while the second separator is joined to its companion. Means, as a latch, retains the support with any one of the material-receiving reels in a position common to all, and in which the material is delivered to them. I have shown the support as having opposite heads, in which are alined depressions to receive reel-spindles. A latch may engage the spindles of one of the two types of reels, material-receiving and web-delivering, to effect the positioning of the plural sets of reels always in predetermined relations.

In the accompanying drawings, in which a particular embodiment of this invention is illustrated,

Fig. 1 shows my improved reeling system in side elevation, parts being broken away;

Fig. 2 is a broken perspective view of the attaching extremity of a slatted separator;

Fig. 3 shows the means for securing this separator to a reel, the view being partly in side elevation and partly in section;

Fig. 4 is a broken end elevation of the reels upon their support, but without the material and separators appearing in Fig. 1;

Fig. 5 illustrates, in side elevation, the means for mounting a reel-spindle upon the support; while

Fig. 6 is a front elevation of the same elements, partly in section.

At the top of a trestle or frame 10 having spaced side members are bearings 12, 12 for

the spindle 14 of a rotatable support 16. This support has opposite heads, in the form of spiders, each with four arms 18 spaced from one another about the axis at equal angles and joined by a central tube 20. At the outer end of each arm is a depression 22 transversely alined with a like depression in an opposite arm to rotatably receive the spindles of reels to be carried by the support. Two of these 10 reels A, A are upon arms separated by 180 degrees from each other, and receive the material M to be coiled, while reels B, B upon the intermediate arms, similarly spaced, deliver a separator S to be wound with the material. The reels may be identical in construction, each having a tubular core 24, and terminal flanges, at the ends of which are bolted sheet-metal heads 26. Into the opening through each core is forced a spindle 27 15 angular in cross-section, here shown as square. Each spindle has, near its opposite ends, a cylindrical portion 28 adapted to enter any one of the depressions 22 and rotate therein. These journal-portions may be held against 20 displacement from the depressions by pins 30 passing through alined openings at opposite sides of the depressions and removably retained by spring-fingers 32 secured to the support and engaging the heads of the pins. 25 To allow the separator S to be secured and released readily from the reels B, B, each reel has, near the opposite extremities of its core, a tubular socket 34. About the interior of each socket is a groove 36 (Fig. 3) to receive a circular spring 38. The separator S 30 comprises spaced chains 40, 40 connected by a series of transverse bars 42. From the terminal links of the chains project studs 44, 44 having rounded ends and of such a diameter 35 as to enter the sockets 34. About the body of each stud is a circumferential groove 46, which, when the stud is forced into the socket, receives the spring 38 and thus releasably attaches the separator S to the reel. When 40 the web of material and this separator are wound together, the former rests over the bars between the chains in a spiral chamber, which protects its surfaces from pressure.

Since the soft yieldable material may not 45 be fully held against contact between adjacent convolutions by the separator S with its spaced bars, or may be marred by the contact of said bars, it may sometimes be desirable to combine with this barred separator a continuous separating web s, which 50 may be of relatively thin fabric treated to prevent the adhesion of such substances as rubber. Projecting from the heads of the support 16 between the pairs of arms 18 are 55 opposite outwardly extending arms 48, 48. Their outer extremities lie beyond the runs of the separator S as it passes between the reels B and A. In the ends of these arms 48 are mounted spools or reels 50, 50 of the separator s. The manner in which the reels 50

are supported and retained upon their arms may be the same as for the reels A and B. Near the corners of the free end of each web s when it is coiled upon its reel 50, are sockets 52, which may be pressed into engagement 70 with studs 54 carried by the last bar of the corresponding separator S. Thus the separator s may be attached to the separator S and a reel A to advance when the reel is 75 rotated.

The material which is to be coiled upon either of the reels A may be delivered by calender-rolls R. A mass of rubber-stock r, subjected to the action of these rolls, passes between successive pairs and emerges as a 80 ribbon or web M upon an endless conveyor C, the travel of the elements being in the directions indicated by the arrows in Fig. 1. From the conveyor, the end of the web is led upon the end of a separator attached to one 85 of the reels A carried by the support 16. To maintain the chosen reel in its receiving relation, there is pivotally mounted upon each side of the frame, at 56, a latch 58, shown as weighted at 60 to urge a depression 62 in 90 its under side toward the path of the projecting ends of the reel-spindles 27. In each spindle-end is formed a peripheral groove 64, each latch and its group of grooves lying in the same vertical plane. When the latches 95 engage the grooved portions of either of the spindles of the reels B, the companion reel A will be correctly secured to receive the advancing material from the rolls R and conveyor C. Inclined surfaces 66, 66, situated 100 upon opposite sides of the depression 62 in each latch and converging toward it, serve, under the influence of the spindles 27 approaching from either direction, to lift the latch and permit its depression to fall into 105 retaining engagement with the spindle.

I have shown the reels A as arranged for manual rotation to coil the material and separators upon them, a crank 68 being applied to the squared end of the spindle 27 of 110 the reel which is in the receiving position, and turned by the operator.

In making use of the system, empty material-reels A, A are applied to the engaging 115 portions of opposite arms 18, 18 of the support and full reels B, B of the separators S to the intermediate arms. Assuming that the separator s is also to be employed, reels 50 of this are placed upon the support-arms 48, 48. The support is retained by the latches 58 with 120 one of the reels A in co-operation with the source R, C of the material to be coiled. At each of the reels A, the separator S, led from the adjacent reel B, is attached by the sockets 34 and studs 44. The separator s is joined to 125 each reel A, through its connection to the associated separator S, by the sockets 52 and studs 54. Now the web M of material fed forward from the calender-rolls R by the conveyor C is placed by the operator upon 130

the separator at the alined reel A, and the crank 68 rotated in a clockwise direction, as viewed in Fig. 1 of the drawings. In this manner, a coil of the material is formed upon 5 the reel, the convolutions being protected from one another by the interposed separator or separators. This continues until the reel A is full and the reels B and 50 empty. Thereupon, the latches 58 are raised to release the 10 support, this causing the unbalanced weight of the full reel to turn the support anti-clockwise (Fig. 1). This reel A will thus be carried past the position in which its associated reel B was located during the winding 15 operation, and at least partially through 180 degrees of movement, there being but slight added effort on the part of the operator required to effect this semi-rotation. This brings what was the upper reel B into the 20 lowermost position, when the latches may be released by the operator and his helper, and contact of the spindle of the reel B with one of the surfaces 66 of each latch will raise this, so that it will be permitted to descend into 25 locking engagement with the groove 64 of the spindle. There is now an empty reel A in receiving relation to the material-delivering conveyor C, together with full reels B and 50 with their separators attached to this reel 30 A. The reel A, just filled, with its empty separator-reels B and 50 are in the opposite positions. After the advancing end of the web of material M has been started upon the newly presented reel A and is being coiled 35 thereon, the full reel A and the empty reels B and 50 may be taken from the support while the winding operation is progressing, and replaced by an empty material-reel and full separator-reels, the ends of the separators being joined to the reel A, as already indicated. These await the completion of the reeling 40 operation, whereupon the reversal of the reels may be effected, as just outlined.

Having described my invention, what I 45 claim as new and desire to secure by Letters Patent of the United States is:

1. The combination with a frame, of a support rotatable upon the frame and having opposite heads provided with a plurality of 50 pairs of alined engaging means, a plurality of reels, each having a spindle held rotatably upon the support by a pair of the engaging means and being revoluble by the support, and retaining means for the support movable 55 upon the frame by the spindles in their revolution and arranged for retaining engagement with said spindles.

2. The combination with a frame, of a support rotatable upon the frame and having 60 opposite heads provided with a plurality of pairs of alined engaging means, a plurality of material-receiving reels, each having a spindle held rotatably upon the support by a pair of the engaging means, arms extending 65 from the heads beyond the engaging

means, a plurality of separator-delivering reels rotatable upon the heads in co-operation with each of the material-receiving reels, and a plurality of separator-delivering reels 70 rotatable upon the arms outside the paths of the separator between the receiving reels and the delivering reels first mentioned.

3. The combination with a frame, of a support rotatable upon the frame and having opposite heads provided with a plurality of 75 pairs of alined engaging means, a plurality of material-receiving reels, each having a spindle held rotatably upon the support by a pair of the engaging means, separator-delivering reels rotatable upon the heads between the material-receiving reels, and a latch movable upon the frame and arranged 80 for retaining engagement with the spindles of one of the two types of reels, said spindles being free for rotation independently 85 of the latch during such engagement.

4. The combination with a frame, of a support rotatable upon the frame and having opposite heads provided with a plurality of 90 pairs of alined engaging means, a plurality of reels, each having a spindle held rotatably upon the support by a pair of the engaging means, and retaining means for the support movable upon the frame and arranged for engagement with the spindles of 95 a portion only of the reels and to be moved thereby for such engagement, the thus-engaged spindles being free for rotation independently of the latch during such engagement. 100

5. The combination with a frame, of a support rotatable upon the frame and having opposite heads provided with a plurality of pairs of alined engaging means, a plurality of material-receiving reels, each having a 105 spindle held rotatably upon the support by a pair of the engaging means, separator-delivering reels rotatable upon the heads between the material-receiving reels, and a latch movable upon the frame and arranged for retaining engagement with the spindles of one only of the two types of reels, said 110 latch being arranged to be moved by contact with the spindles in preparation for such retention and leaving said spindles free to rotate while thus retained.

6. In a reeling system, a movable support, a material-receiving reel provided with a portion of a securing device and rotatable upon the support, a reel rotatable upon the support and containing a coil of separator having at its outer extremity another portion of the securing device attached to that portion upon the receiving reel, said separator carrying a portion of a second securing device, and still another reel rotatable upon the support and containing a coil of separator with a portion of the second securing device at its outer extremity attached. 115 120 125 130

to that portion upon the first-mentioned separator.

7. In a reeling system, a rotatable support, opposite material-receiving reels each provided with a portion of a securing device and rotatable upon the support, a pair of reels rotatable upon the support and each containing a coil of separator having at its outer extremity another portion of the securing device attached to that portion upon one of the receiving reels, said separator carrying a portion of a second securing device, and still another pair of reels rotatable upon the support, each of said reels containing a coil of separator with a portion of the second securing device at its outer extremity attached to that portion upon one of the first-mentioned separators.

8. In a reeling system, a rotatable support, opposite material-receiving reels each provided with a portion of a securing device and rotatable upon the support, a pair of reels rotatable upon the support and each containing a coil of separator comprising transversely extending spaced bars and having at its outer extremity another portion of the securing device attached to that portion upon one of the receiving reels, said separator having mounted upon one of its bars a portion of a second securing device, and still another pair of reels rotatable upon the support, each of said reels containing a coil of separator-web with a portion of the second securing device at its outer extremity attached to that portion upon the bar of one of the first-mentioned separators.

In testimony whereof I have signed my name to this specification.

ERNEST W. STACEY.
